TOOLHOLDER

Thomas S. Shaw, Detroit, Mich., assignor to
Wilfrid G. Torrance, Detroit, Mich.

Application February 28, 1938, Serial No. 193,043

2 Claims. (Cl. 279—87)

My invention relates to a new and useful improvement in a toolholder adapted especially for holding a punch, a die or the like so that the same may be readily mounted in position and easily 5 and quickly removed and replaced when desired.

It is an object of the present invention to provide a toolholder of this class which will be simple in structure, economical of manufacture, durable, compact and free from any resilient or spring-like parts.

10 It is another object of the invention to provide a toolholder having a structure whereby the tool may be positively locked in position and prevented from dislodgement from the holder.

15 Another object of the invention is the provision of a toolholder of this class having a plurality of axially directed parallel extending passages in which cooperating parts are positioned.

Other objects will appear hereinafter.

20 The invention consists in the combination and arrangement of parts hereinafter described and claimed.

The invention will be best understood by a reference to the accompanying drawing which 25 forms a part of this specification and in which:

Fig. 1 is a central, vertical, sectional view of the invention.

Fig. 2 is a sectional view taken on line 2—2 of Fig. 1.

30 Fig. 3 is a sectional view taken on line 3—3 of Fig. 1.

In the drawing I have illustrated the invention adapted for use in retaining a punch in position. From the description, however, it will be obvious 35 that it is equally well adapted for retaining a die or other similar tool in a holder. The invention comprises a retaining block 9 which is secured by screws 10 or in any other suitable manner to a punch plate 11 projecting outwardly from

40 which are dowels 12 which engage in pockets 13 formed in the face 14 of the retainer 9. The central portion of the retainer is recessed as at 15 and pressed into this recess is a hardened and ground plate 16 which serves as an abutment for

45 the tool retainer by the holder. Formed centrally in the retainer or block 9 is a passage 17 which terminates at the inner face of the abutment plate 16. Extending through the retainer 9 and terminating at the abutment plate 16 is a

50 comparatively narrow slot 18 having the inclined wall 19. This slot 18 opens throughout its length into the passage or bore 17. Slideably positioned in the slot 18 is a locking plate 20 which is also provided with an inclined edge 21. Threaded 55 into the threaded socket 22 formed in the re-

tainer 9 is the screw 23 having a head 24 which is adapted to overlie the slot 18. This head 24 being positioned in a recess 25 formed in the retainer 9.

The tool adapted to be secured by the retainer 5 is provided with a shank 26 having a longitudinally directed peripheral groove 27 formed therein and in which the edge of the locking plate 20 is adapted to engage. This plate 20 is of such width that when positioned in the slot 18 10 with its outer end substantially flush with the outer face 28 of the retainer 9, the locking plate 20 will clear the bore or passage 17. When the tool shank 26 is positioned in the passage or bore 17, the inner end thereof will engage against the 15 face of the abutment plate 16 and when the shank 26 is rotated so that the groove 27 registers with the slot 18, a threading inwardly of the screw head 24 will force the locking plate 20 20 inwardly and as it moves inwardly of the slot 18, toward the abutment plate 16, it will move radially 25 of the tool shank 26 and engage in the groove 27 and serve to clamp the tool shank 26 in the bore 17 and force it tightly against the face of the abutment plate 16. This is due to the fact 25 that the groove 27 has an inclined terminal portion 29 clearly illustrated in Fig. 1. Consequently by threading the screw head 24 inwardly and forcing the locking plate 20 inwardly, the tool shank 30 not only is locked against undue removal from the retainer 9 but is forced securely against the abutment plate 16 so that a positive lock is thus provided which will prevent any looseness of the associated parts or any play of the same while 35 in use.

When it is desired to remove the tool from the retainer 9, it is but necessary to thread the screw head outwardly permitting the plate to move outwardly of its slot 19 until it has disengaged from the groove in the shank 26 whereupon the 40 shank 26 may be removed by hand. It is obvious that when the shank 26 is in the depending relation to the retainer 9, it will drop out of the passage or bore 17 when the locking plate 20 is moved to inoperative position. It will be noted 45 also that once the parts are assembled, the locking plate is not removed from its slot in order to remove the tool shank from the passage 17 as the screw 23 is of sufficient length to permit the 50 backing outwardly of the plate 20 to releasing or inoperative position without permitting the plate 20 to become disengaged from the slot 18. The width of the plate 20 is of such dimensions, 55 relatively to the diameter of the passage 17, that 55

it cannot become dislodged from the slot 18 by tilting over into the passage or bore 17.

In this manner, I have provided a simple, economically manufactured and durable retainer of the releasable type in which the use of springs or other resilient or yieldable means is entirely eliminated and in which a positive locking of the tool in the holder is effected.

While I have illustrated and described the preferred form of construction, I do not wish to limit myself to the precise details of structure shown, but desire to avail myself of such variations and modifications as may come within the scope of the appended claims.

15 15. What I claim as new is:

1. A toolholder of the class described, comprising: a retainer having a tool receiving passage formed therein adapted for the reception of a tool shank; a tool shank inserted in said passage and having an axially extending peripheral groove formed therein diminishing in depth proceeding toward the end of said tool shank, said retainer having a second passage formed therein extending inwardly from one end thereof and axially of said first named passage and opening at one side thereinto and having an inclined surface at the opposite side; a wedge-shaped locking plate slideably mounted in said second passage through its open end and adapted upon inward movement therein for projecting at one side into said tool receiving passage and engaging in the groove in the tool shank therein;

and means engageable with said locking plate for forcing the same inwardly of said second named passage, the inward movement of said locking plate forcing said tool shank inwardly of said first named passage and clamping said tool shank 5 against removal therefrom.

2. A toolholder of the class described, comprising: a retainer having a tool receiving passage formed therein adapted for the reception of a tool shank; a tool shank positioned in said passage and having a peripheral axially directed groove formed therein diminishing in depth toward the end thereof, said retainer having a second passage therein extending inwardly from one end thereof and axially of said first named 15 passage and opening at one side thereinto and having an inclined surface at the opposite side; a wedge-shaped locking plate slideably mounted in said passage and adapted upon inward movement thereof for projecting at one side into said tool receiving passage and engaging in the groove in the tool shank therein for forcing said tool shank inwardly of said first named passage and clamping the same therein, said shank engaging 20 side of said plate and the opposite side of said plate being inclined to the axis of said plate and converging toward the inner end of said plate; and threaded means on said retainer adapted upon threading for forcing said locking plate inwardly of said second named passage.

25 THOMAS S. SHAW.
